HOLDER FOR MOPS AND OTHER ARTICLES

John W. Martin, Brooklyn, N. Y.

Application August 22, 1942, Serial No. 455,969

3 Claims. (Cl. 15—150)

This invention relates to holding or gripping devices for mops, brushes, tools and other articles.

One object of the invention is to provide a device of the character described which can be caused to grip a mop without holding the mop in one's hand.

Another object of the invention is the provision of a device of the nature set forth which can be made to be forced into engagement with a mop or the like with sufficient tightness determined by direct pressure on a jaw of the device.

Another object of the invention is to furnish a device of the type mentioned wherein the mop may be removed by releasing the lock of the device, without the need for grasping the mop in one's hand.

Heretofore many types of mop holders have been provided, which required that the mop be inserted into the holding device by hand, and similarly removed therefrom. A mop is often rather dirty, even after it has been rinsed out, and particularly is this so, where the rinsing is repeated in a pail of water, according to the usual custom. Applicant perceived that if he could provide a device which could grip and release a mop without requiring that it be touched by hand, a long felt public need would be solved. To facilitate the operation, applicant went a step further and provided a device capable of gripping the mop sufficiently tightly so that no further manipulation was required to assure a reliable securement of the mop.

It is therefore another object of the invention to provide a mop holder or the like capable of receiving a mop by a scooping action of a jaw.

Another object is to provide improved means such that the scooped mop is gripped by pressing on the usual long handle to force a jaw against the ground or floor and thus actuate the locking means in proportion to the force with which the jaw is pressed on the ground.

Another object of the invention is to afford a simple release for the lock whereby the jaws can separate to drop the mop.

Still another object is to furnish a mop holder which shall grip a mop at offset lines to produce a bend at the gripped area of the mop for more securely holding the same.

Since the improved locking device for the mop holder comprises a ratchet-like clutch, it is often difficult to obtain as accurate an adjustment in locking tension as with a simple screw, for instance. Accordingly it is desirable to afford increased cushioning engagement to enhance the range of the jaws in gripping a mop. This is

readily effected by making one of the jaws longer than the other to produce the offset lines of gripping.

It is therefore another object of the invention to provide a mop holder having a ratchet-like lock for jaws one of which is substantially longer than the other for a superior engagement with the mop.

Another object is to so construct the mop holder that the movable jaw which actuates the locking clutch extends laterally of the holder in open position so that such jaw can be readily moved by downward pressure on the ground.

Another object is to so arrange the mop holder that the longer jaw serves as the scoop for the mop and as the actuator for the locking clutch.

Still another object of the invention is to furnish a holder for mops and the like which shall be simple and inexpensive to manufacture, durable, reliable, easy and convenient in use, which shall be small and compact, free of any projecting parts which might damage furniture, and which is capable of being made substantially entirely of non metallic materials such as wood or plastic.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designed by the same reference characters throughout the several views.

In the drawing:

Fig. 1 is a plan view of a holding device embodying the invention with part of the handle removed.

Fig. 2 is a section on the line 2—2 of Fig. 1, with the handle removed, and positioned for scooping a mop on a floor against which the movable jaw is pressed to close and lock the device, another succeeding position of the pawl and movable jaw being shown in dot-dash lines with parts removed.

Fig. 3 is a section on the line 3—3 of Fig. 2.

The advantages of the invention as here outlined are best realized when all of its features and instrumentalities are combined in one and the same structure, but, useful devices may be produced embodying less than the whole.

It will be obvious to those skilled in the art to which this invention appertains, that the same

may be incorporated in several different constructions. The accompanying drawing, therefore, is submitted merely as showing the preferred exemplification of the invention.

Referring in detail to the drawing, 10 denotes a device embodying the invention. The same may be regarded as a tool holder and preferably as a device for picking up and gripping an article for such a purpose or use as may be desirable. The advantages of the invention are best exemplified in a mop holder, especially as it is believed to fill a long felt need in this art and to possess numerous advantages therefor. Accordingly the drawing shows the invention embodied in a device for holding a mop, but it may also be used to hold a broom head, and it may, with suitable modification of the jaws, hold a tool, or grab a miscellaneous article which is to be carried from one point to another.

The device 10 may include a long handle 11, which may be straight or of other suitable form, and carries at its lower-end a means 12 for operatively mounting a plurality of jaws. For instance the means 12 may have a bore or square chamber 13 into which the handle 11 is press fitted. Of the jaws, at least one is pivotally movable, and the other may be stationary. Thus the jaw 14 is integral with the supporting means 12 and may be generally parallel or in alignment with the handle 11. The other jaw 15 may be mounted for angular movement in any suitable manner on the support 12, for instance, on a fulcrum 16. One of the jaws, preferably 15, is substantially longer than the other, and it or both jaws may have opposed end lips 17, 18 which are thus offset from each other, to grip a mop at spaced lines. Thus the gripped or compressed portion of the mop is curved, by co-operation with the main or relatively plane portions of the jaws. Accordingly the mop is subjected to combined compressive and twisting actions, so that a superior grip on the mop is obtained. This feature is of general advantage, and possesses specific utility herein, because it increases the range of compression within which the device 10 can reliably grip the mop without requiring the accurate jaw adjustment afforded by a clamping screw as heretofore used, and hence is of aid to the feasibility of the simple, highly compact and strong ratchet-like clutch hereinafter described.

Operatively arranged with the movable jaw 15 is a clutch device which may be frictional or positive in character, at least in one direction to prevent or resist separation of the jaws while permitting free or relatively free movement of the jaw 15 toward the companion jaw for clamping an article. Preferably the clutch is in the nature of a ratchet-like device which may comprise a ratchet-like member or rack 19 and a therewith locking or pawl-like member 20. One of these members may be mounted on either jaw and the other on the other jaw. Preferably the toothed member 19 is fixedly connected to the movable jaw 15 and the pawl-like member 20 is pivotally mounted on the stationary jaw 14 as at 21. In a broader sense, one of the members 19, 20 may be regarded as mounted on the stationary means 12.

If the parts 12, 14, 15 and 20 be made of plastic material the walls thereof may be rather thick as shown. To limit the use of metal even for the fulcrums, the portion 16 may be cast integral with the support 12, being carried by the side walls or flanges 22 of the support 12 and

the fixed jaw 14. In that case the movable jaw 15 may be formed with an open bearing which can be resiliently spread and snapped on the fulcrum 16. The shank 23 of the fulcrum should be at such an angle as to be in direct compression when the pawl 20 pulls the jaws 14, 15 together. Moreover, the end of the jaw 15 may have some bearing engagement at 24 with the support 12 so that the component of force of the angular pawl 20 may be directly assumed by the bearing surfaces. The rack part 19 of the movable jaw may be of sufficient width to fill the space between the flanges 22 for ample bearing engagement with the pawl 20 which may be of like width. While the pawl may gravitationally engage the teeth of the member 19, it is preferred that it be actuated as by a sheet spring 25, and to release the pawl, a finger piece 26 extends therefrom to accommodate these parts; the fixed jaw 14 may have an opening 27 through which the pawl and spring 25 extend, and a recess 28 adapted to partially receive the finger piece 26. The angle shaped spring 25 may be secured to the jaw 14 and arranged for sliding bearing pressure on the pawl. This spring may be of metal pinned or otherwise affixed to the jaw 14, or of plastic cemented or autogenously united thereto.

An important feature of the structure is that the pawl 20 terminates in a hook 29, and the teeth 30 of the ratchet member 19 are at a like angle for a hooked engagement. The arrangement is further such that when the movable jaw 15, acting as a scoop, is pushed under a portion of a mop or other article lying on a floor 31, the handle 11 may be pushed down to exert pressure on the movable jaw to cause the pawl hook 29 to ride along the teeth 30 for successive locking engagement therewith to cause the device 10 to be clamped on the mop. To release the latter it is sufficient to merely press down on the finger piece 26, to swing the pawl 20 against the force of the spring 25 for thus releasing the tooth 30 to permit separation of the jaws.

Since the radius of action of the ratchet-like device 19, 20 is rather limited, room for only 3 or 4 teeth 30 may be obtained. Hence the offset relation of the jaw lips 17, 18 is of advantage because thus a greater range of clamping compression on the mop is afforded for securely holding the same. By the arrangement described, the jaws 14, 15 afford therebetween a chamber for completely housing the pawl and ratchet device to avoid projecting parts which might damage furniture. Moreover, it is seen that the pawl 20 should lie at an acute angle to the jaws for exerting a transverse component of tension, and therefore the axial points at 16 and 21 must be spaced apart transversely of the device. The acute angle position also assists in preventing accidental premature closing movement of the jaw 15, because the spring 25 and curved teeth 29 permit the pawl to act as a releasable abutment. To insure a sufficient number of teeth 30 for the relatively small angular movement of the jaw 15, the pawl 20 should be rather short, and the pivotal point 16 should be more remote from the free end of the jaws than the fulcrum at 21.

To facilitate the desired manner of use of the device 10, it is preferable that the longer of the two jaws be the movable one, and it is desirable that it shall extend laterally, especially in the open position. Thus it is quite convenient to use the movable jaw 15 as a scoop for the mop and to receive the downward pressure whereby the jaw 15

serves as an actuator for the locking device 19, 20. Thus the mop may be gripped and clamped without the need for soiling one's hands, and it may be released by operation of the finger piece 28 to permit the mop to drop out of the holder, so that the mop need not be directly handled. It will thus be seen that the device fulfills all the objects of the invention and is well adapted for practical use.

I claim:

1. A device including a holding means having a jaw fixed with respect to a rearwardly extending handle, a scoop-shaped jaw pivoted with respect to said first jaw and handle, said jaws having their free ends extending forwardly of said handle and said pivoted jaw being positioned opposite said first jaw, means located between the jaws wholly between the pivot and the free ends of the jaws, including a toothed rack on and extending lengthwise of the movable jaw, an elongated pawl pivoted at its rear end on the fixed jaw whose pivot is spaced above and in advance of the pivot of the movable jaw, the major dimension of said pawl thus forming an acute angle with the lengthwise extent of the rack, the free end of the pawl and the rack teeth being of hooked form, so that the pawl acts in tension to prevent separation of the jaws, means for limiting to an open set position the opening movement of the pivoted jaw with respect to the fixed jaw and handle, and a spring for the pawl urging the latter in such direction that it engages and tends to retain the movable jaw in set open position.

2. A device including a holding means having a jaw fixed with respect to a rearwardly extending handle, a mop-scooping jaw pivoted with respect to said first jaw and handle, said pivot being downwardly spaced from the end portion of the fixed jaw that is connected to the handle, said jaws having their free ends extending forwardly of said handle and said pivoted jaw being positioned opposite to said first jaw, means located

between the jaws wholly between the pivot and the free ends of the jaws, including a forwardly, downwardly sloping toothed rack on and extending lengthwise of the movable jaw, an elongated 5 downwardly and forwardly sloping pawl pivoted at its rear end on the fixed jaw whose pivot is spaced above and in advance of the pivot of the movable jaw, the major dimension of said pawl thus forming an acute angle with the lengthwise 10 extent of the rack, the free end of the pawl and rack teeth being of hooked form, so that the pawl acts in tension to prevent separation of the jaws, said pawl normally swinging about its pivot downwardly toward the sloping rack for engagement 15 with the teeth thereof.

3. A device including a holding means having a jaw fixed with respect to a rearwardly extending handle, a jaw pivoted with respect to said first jaw and handle, said jaws having their free ends extending forwardly of said handle and the pivoted jaw being positioned opposite to said first jaw, means located between the jaws wholly between the pivot and the free ends of the jaws, including a toothed rack on and extending lengthwise of the movable jaw, an elongated pawl pivoted at its rear end on the fixed jaw whose pivot is above and in advance of the pivot of the movable jaw, the free end of the pawl and the rack teeth being of hooked form, so that the pawl acts in tension to prevent separation of the jaws, the upright spacing between the pivot of the movable jaw and the pivot of the pawl being sufficient so that the major dimension of the pawl forms an acute angle with the lengthwise extent of the rack, with the acute angle rapidly diminishing as the movable jaw is swung toward the fixed jaw for closing on a mop, and with the pawl tooth being manually disengageable from a hooked tooth of the rack at said different angles, and means for so manually disengaging the pawl by 20 swinging the same away from the rack.

JOHN W. MARTIN.
